UNITED STATES PATENT OFFICE

EDWIN W. BULLINGER, OF BROOKLYN, NEW YORK.

IMPROVEMENT IN TEMPORARY BINDERS.

Specification forming part of Letters Patent No. 150,520, dated May 5, 1874; application filed September 12, 1873.

To all whom it may concern:

Be it known that I, EDWIN W. BULLINGER, of Brooklyn, in the county of Kings and State of New York, have invented Improvements in Temporary Binders, of which the following is a specification:

These improvements relate particularly to a paper-file patented by J. Nelson Jacobs on June 19, 1860. The invention consists in the combination of pairs of hooks on the inner adjacent edges of the files boards or covers, a spring arranged on one board equidistant from them, and cords extending obliquely from them to the spring, whereby not only is a single spring made to secure both cords, but it also serves to retain them within the hooks, and thus allows the successful use of hooks which are more convenient than eyes in the provision they afford for the easy insertion of new papers in the file.

In the accompanying drawing, Figure 1 is a face view of the improved file open; and Fig. 2 is a section of the same, taken near the inner edge of one of the boards or covers, as indicated by the dotted line *xx* in Fig. 1.

Similar letters of reference indicate corresponding parts in both figures.

A A are the two boards or covers of the file. They are united, in the usual way, by a flexible back, and thus constitute a portfolio. Instead of the eyes generally employed at their inner edges to fasten thereto the cords C C, that hold the papers in place, I use hooks B B, which are arranged with their ends pointing outward in the direction of the end edges of the boards. On one of the boards, near its outer side edge, there is arranged, equidistant from its hooks B B, a spiral spring, E, which is slightly flattened to prevent it from adding to the thickness of the file sufficiently to give it an unsightly appearance and to render it incommodious. On the free end of the spring is a hook, D, formed by bending the end portion into the requisite shape. The free ends

of these cords C C are fastened to this hook. Their other ends are made fast to the hooks B B on the edge of the opposite board by slipping their ends over them, or otherwise. On the ends which are threaded through the papers there are tags *a a*, to facilitate the puncturing of the papers necessary for the passage of the cords through them. After leaving the hooks they extend obliquely toward each other till they meet at the spring, wherefore they are retained within the hooks as securely as they would be retained within eyes.

To file papers in this file, the cords are detached from the hook of the spring and slipped out of those hooks B B on the same board as the spring, and are then threaded through the papers. Afterward the cords are slipped into the hooks B B again, and their ends are slipped over the hook D on the spring, or are otherwise fastened to it. The cords are kept taut by the resilience of the spring. It, being arranged equidistant from the hooks B B, through which the cords are last passed, retains the cords therein, because it draws them inward toward each other, as before described.

This file possesses all the advantages of other files of its kind, and, owing to the adaptation of a single spring to both the cords, is much simpler. Moreover, it is handier to use, because the necessity for unthreading and rethreading the cords through eyes every time papers are filed is obviated.

What I claim as my invention is—

The combination of the hooks B B on the edges of the boards, the spring E attached to one board, and the cords extending from the said hooks obliquely to the spring, whereby the spring is made to retain the cords in the hooks, substantially as and for the purpose set forth.

E. W. BULLINGER.
